UNITED STATES PATENT OFFICE.

CLINTON W. HOUGH, OF BOONVILLE, NEW YORK, ASSIGNOR, BY MESNE ASSIGNMENTS, TO WIRED RADIO INC., OF NEW YORK, N. Y., A CORPORATION OF DELAWARE.

LAMP-SOCKET ATTACHMENT DEVICE.

Application filed September 27, 1922. Serial No. 590,797.

To all whom it may concern:

Be it known that I, CLINTON W. HOUGH, a citizen of the United States, residing at Boonville, in the county of Oneida, State of New York, have invented certain new and useful Improvements in Lamp-Socket Attachment Devices; and I do hereby declare the following to be a full, clear, and exact description of the invention, such as will enable others skilled in the art to which it appertains to make and use the same.

This invention relates to lamp socket attachment devices for connecting radio or carrier current or so-called "wired wireless" apparatus to electric light or power lines.

Lamp socket devices embodying fixed condensers for adapting electric light lines for use with radio antennæ have heretofore been constructed, but it has been found that in order to obtain the best results with these devices, the capacity of the condenser must be suited quite exactly to the constants of the particular line to which it is connected, and, as is well known, fixed condensers do not readily lend themselves to adjustment.

The principal object of the present invention is, therefore, the provision of a lamp socket device for the purpose above mentioned having variable capacity whereby it may be readily adjusted to obtain the best results on any lighting or power line to which it may be connected.

Another object of the invention is the provision of a device of the above-mentioned character having a lamp socket as well as plug so that the radio or wired wireless receiving equipment may be connected in without interfering with the lighting arrangements. This is particularly advantageous where the room in which the radio equipment is installed is provided with only one lamp socket.

To these ends a device in accordance with the preferred form of the invention comprises a screw plug designed to fit a standard lamp socket, a socket designed to receive a standard lamp base, a core of insulating material to which both the plug and socket are attached, and a variable condenser, one plate of which may form a connecting link between the plug and socket. The variable condenser, as in the usual type, comprises one or more fixed plates and one or more movable plates, and a suitable binding post or the like is preferably attached

to the movable plate or plates by which connection may be made with the receiving apparatus.

Another contemplated form of the invention is a device similar to that previously described but embodying a fixed condenser or condensers instead of a variable condenser, as in the preferred form. This latter structure, like the former, includes a plug and lamp socket, so that it may be used without interfering with lighting facilities.

In transmitting wired wireless signals over electric lighting circuits usually one side only of the line is employed, the return path being by way of ground. It therefore becomes necessary to arrange the device so that the condenser or condensers may be connected to either side of the line. This is due to the fact that the lamp socket (not the socket included in the device) terminals are connected to the lighting wires arbitrarily—there being no requirement or necessity with regard to the respective terminals of the sockets being connected to any particular side of the lighting circuit. For this reason the lamp socket device of the present invention is preferably made in two separate parts, one of which includes the plug, and the other the lamp socket, together with a condenser or condensers. The latter portion may be connected to the former by a simple insertion of its terminals into an aperture or apertures provided in the plug portion as in plugs ordinarily used on extension cords and the like, and, as will be seen, such an arrangement permits the connections to be readily reversed. However, it has been found that the frictional engagement between the two parts of the device, while ordinarily sufficient to hold them together, is not particularly dependable where any appreciable load is likely to be imposed upon the cord and where, as in the present instance, a lamp may be broken as a result of the two parts of the device being accidentally pulled apart. With the object of obviating this possibility, the present invention includes as one of its features means for positively securing the two parts of the device together so that they cannot be pulled apart by any force which is likely to be applied in ordinary usage. One of the simplest expedients in accordance with this phase of the invention

95

100

105

110

consists in using one or more locking screws arranged to engage a groove or grooves in the inserted terminal or terminals. The locking screws may be, and are preferably, 5 provided with heads of insulating material, so that there is no danger of the operator's hand being connected with a live conductor.

Other features of the invention are to be found in the detailed construction of the 10 several devices described hereinafter, and will be apparent from the description.

In the drawings accompanying this specification Fig. 1 is a longitudinal section of a lamp socket attachment device in accordance 15 with the invention;

Fig. 2 is an elevational view of the device shown in cross section in Fig. 1;

Fig. 3 is a cross-sectional view along the line 3—3 of Fig. 1;

Fig. 4 is an enlarged fragmentary section 20 of the device shown in Figs. 2 and 3;

Fig. 5 is a longitudinal section of an alternative structure in accordance with the invention;

Fig. 6 is an elevational view of the structure 25 shown in Fig. 5;

Fig. 7 is a longitudinal section of another alternative construction showing a two-part device;

Fig. 8 is a cross-sectional view taken along the line 8—8 of Fig. 7;

Fig. 9 is a longitudinal section of another alternative structure including fixed instead 30 of variable condensers;

Fig. 10 is a cross section taken along the line 10—10 of Fig. 9; and

Fig. 11 is a cross section taken along the line 11—11 of Fig. 9.

The devices of Figs. 1 to 6 inclusive are of 40 unit construction, that is they are not so arranged that they may be taken apart and the connections through the condensers reversed, as in the devices of Figs. 7 to 11 inclusive.

In the structure shown in Figs. 1, 2, 3, and 4, core 1 is of insulating material such as porcelain. On the upper end of the core 1 is a two-conductor plug comprising the threaded metal sleeve 2 which forms one 45 conductor, and the rod 3, which extends through the core and is provided with a head 3' at its lower end and a nut 4 at its upper end. The sleeve 2 is designed to screw into a standard lamp socket of the well-known type. To the lower end of the core 1 there is attached a threaded metal sleeve 5 designed to receive the base of a standard 50 incandescent lamp bulb in the manner of an ordinary lamp socket. The sleeve 5 and head 3' of the rod 3 provide contacting media for the lamp. Integral with the sleeve 2 is a semi-cylindrical metallic portion 6 constituting a fixed condenser plate. The sleeve 5 is connected with the condenser 55 plate 6 by means of a metallic strip or wire

7. Thus it will be seen that sleeves 2 and 5 are electrically connected through the condenser plate 6.

A semi-cylindrical metallic plate 8 is disposed coaxially with the fixed plate 6 and 60 insulated therefrom by means of a member 9 of fibre or other suitable insulating material. The upper edge portion 9' of the member 9 is folded back, as is more clearly shown in Fig. 4, to form a channel in which the plate 8 is slidably retained. The thickness of the member 9 may be, and is preferably, very much thinner than illustrated. The movable plate 8 is movable through an angle of 180°, and is shown in the position 65 of maximum capacity in Fig. 3. The binding post 10 is secured to the movable plate and is adapted to be operated not only as a binding post for effecting connections between the movable plate and the radio apparatus, but also as a handle for adjusting the movable plate. The entire device with the exception of the movable plate is enclosed within a metal casing comprising parts 11 and 12, which are secured together by means 70 of screws 13. The metal casing is separated from the other metallic portions of the device by means of suitably shaped insulators 14 and 15, and a slot 11' is provided in the part 11 to permit the necessary movement 75 of binding post 10.

While in the device of Figs. 1, 2 and 3 only one fixed and one movable condenser plate are shown, it will be obvious that a device of the same character may be readily designed 80 having a greater number of condenser plates, and such a device is within the spirit and scope of this invention.

In the alternative structure of Figs. 5 and 6 the metal socket sleeve 16 functions as a 85 fixed condenser plate in addition to operating in the usual manner as in a lamp socket. A tube of insulating material 17 encloses the sleeve 16 and is secured in any suitable manner to the core 18. The movable condenser plate in the form of a cylindrical sleeve 19 is mounted on the outside of the tube 17 and coaxially therewith, and is provided with a punched out finger portion 19', which is arranged to press against the tube 17. The condenser plate 19 is slidable along the tube 17, and by virtue of the finger 19' will remain in any position in which it is set. It will be seen that the movable plate 19 is shown in its position of minimum capacity. When the latter plate is moved into its lowermost position the maximum capacity is obtained. Any capacity between the maximum and minimum limits may thus be 100 readily obtained by simply adjusting the position of the condenser plate 19. The separation between condenser plate 19 and tube 17 shown at the right of Fig. 5 is greatly exaggerated for the purpose of more clearly illustrating the finger 19'. In prac- 105

tice this separation would be very slight. The socket sleeve 16 and plug sleeve 20 are electrically connected by means of a metal strip 21, which is riveted to socket sleeve 16 and preferably soldered to the plug sleeve 20. The binding post 22 is provided for establishing connections with the radio or wired wireless receiving apparatus.

The alternative structure of Figs. 7 and 8 is a two-part device of which the upper or plug portion comprises a porcelain core 23, a threaded metal sleeve 24 secured to the core 23, and a metal tip 25 embedded in the end of the core 23. A pair of contact springs 26 and 27 having their ends suitably formed, as shown, are embedded in the porcelain core 23, and extend into the recess 23'. These contact springs are connected respectively to sleeve 24 and the tip 25 by suitable conductors. The lower portion of the device comprises a porcelain core 28 into which are embedded a pair of metal plugs 29 and 30, the ends of which are suitably formed to cooperate with the free ends of the contact springs 26 and 27 in such a way that the tension of the latter springs tends to hold the plugs in engagement therewith and consequently to hold the two parts of the device together. Each of the plugs 29 and 30 is provided with a V-shaped groove suitably disposed to be engaged by the pointed ends of the locking screws 31 and 32. These locking screws are preferably provided with heads of vulcanized rubber or other suitable insulating material to protect the operator from connecting with a live conductor. With the lower portion of the device engaged with the upper portion as shown, and the two locking screws adjusted to engage the plugs as illustrated, the two parts are firmly secured together and cannot be separated by any ordinary force which is likely to be applied. The condenser element of the present device comprises the metal socket sleeve 33, functioning as a fixed condenser plate, and the adjustable plate 35, which is arranged for longitudinal movement and may be provided with a spring finger similar to 19' in Fig. 5. The two condenser plates 33 and 35 are insulated by a thin tube 36, which may suitably be of fibre or other insulating material. The metal tip 37 is also embedded in the core 28 to provide a contact for a lamp. Sleeve 33 is connected with plug 29 by conductor 34, which may be of wire, and tip 37 is connected to plug 30 by conductor 38, which may also be of wire. It will be seen that by withdrawing the lower portion of the device the connection may be reversed. That is to say, plug 29 may be connected with contact spring 27 and likewise plug 30 connected with contact spring 26. Thus the fixed plate of the condenser may be connected to either side of the lighting circuit.

The structure of Figs. 9, 10 and 11 is similar to devices which have heretofore been proposed in that it utilizes fixed instead of variable condensers, but differs from prior structures by the provision of a lamp socket which makes it unnecessary to disrupt the lighting facilities of a room when using the device. The upper or plug portion of this structure comprises a core 39 of insulating material, a threaded metal sleeve 40 designed to fit a standard lamp socket, a bolt 41 the head of which forms a contact for engaging with the center contact of the lamp socket, the lower end being threaded for engaging the nut 42, and having a V-shaped groove for engaging contact spring 46 in the lower portion of the device. A metal plug 43 is also embedded in the core 39 and connected with the sleeve 40 by the conductor 44. This plug is provided with a V-shaped groove similar in all respects to the groove provided on the bolt 41, and is adapted to engage contact spring 45. The plug portion of the device also includes a pair of suitably shaped contact springs 47 and 48, which are connected respectively with the bolt 41 and the sleeve 40. These springs 47 and 48 are offset at their end portions so as to register with apertures in the flat strips 49 and 50, as is clearly shown in Fig. 9. By virtue of the engagement thus effected between springs 47, 48 and strips 49, 50 as well as between springs 45, 46 and the plug 43 and bolt 41, the upper and lower portions of the device are quite rigidly secured together, and are not likely to be pulled apart by any ordinary force which might be applied in usage. The lamp socket comprising a part of the lower portion of the device includes a metal insert 51 which is connected with contact spring 46 and a threaded metal sleeve 52 which is connected with contact spring 45. The metal strips 49 and 50 are connected respectively with a pair of small fixed condensers 53 and 54, the details of which need not be shown, as they are well known in the art. Each of these condensers is connected, as shown, with a suitable binding post 55, 56. The lower portion of the device may be, and is preferably, enclosed in a tubular casing 57 of insulating material such as vulcanized fibre. The core 58 is preferably made with a chamber 58' for receiving the condensers 53 and 54, and the space within the chamber surrounding the condensers may be filled with one of the well-known beeswax or paraffin compounds such as are extensively used in the condenser art.

Although the invention is here disclosed in only a few forms, it will be understood that it may be readily embodied in many additional forms, and accordingly it is not

to be limited except by the scope of the appended claims.

I claim:

- 5 1. In a lamp socket attachment device, a plug adapted to be inserted in a lamp socket, a multiplate variable condenser, having at least one plate electrically connected with said plug, said plug and condenser being combined to form a rigid, self-contained unitary structure.
- 10 2. In a lamp socket attachment device, a plug adapted to be inserted in a lamp socket, a multi-plate variable condenser having at least one plate electrically connected with said plug and a lamp socket electrically connected with said plug, said plug, condenser and lamp socket being combined to form a rigid self-contained unitary structure.
- 15 3. In a lamp socket attachment device, a plug adapted to be inserted in a lamp socket, a variable condenser comprising a plurality of coaxial plate elements, at least one of said plate elements being electrically connected with said plug, said plug and condenser being combined to form a rigid, self-contained unitary structure.
- 20 4. In a lamp socket attachment device, a core of insulating material, a plug attached to said core and adapted to be inserted in a lamp socket, a fixed condenser plate mounted on said core and coaxial therewith, said fixed plate being connected with said plug, and a movable condenser plate mounted coaxially with said fixed plate and adapted to cooperate therewith.
- 25 5. In a lamp socket attachment device, a core of insulating material, a plug attached to said core and adapted to be inserted in a lamp socket, a socket attached to said core and adapted to receive an electric lamp, a variable plate condenser mounted on said core, at least one plate of said condenser being electrically connected with said plug.
- 30 6. In a lamp socket attachment device, a plug adapted to be inserted in a lamp socket, a socket adapted to receive an electric lamp, a variable plate condenser, and means including a plate of said condenser for interconnecting said plug and said socket.
- 35 7. In a device for completing electrical connections between a power line and a signaling apparatus, the combination of a body portion, a screw plug formed on one end of said body portion and arranged to make connection with a standard lamp socket supplied from power lines, a screw socket carried by the other end of said body portion, a variable plate condenser positioned in said body portion and adjustable from the exterior of said body portion, and a connection from one side of the power line in its passage from said screw plug to said screw socket with said variable condenser, and means for varying the capacity of said condenser for selectively varying the coupling

between exterior electrical circuits and said power supply line.

8. In a lamp socket attachment device, a plug adapted for insertion in a standard lamp socket, a member including a condenser, contacting elements for yieldably securing said plug and said member together, said elements being connected to said plug and said condenser respectively, and means for positively securing said plug and said member together.

9. In a lamp socket attachment device, a plug adapted for insertion in a standard lamp socket, a member including a condenser, contacting elements for yieldably securing said plug and said member together, said elements being connected to said plug and said condenser respectively, and a locking screw for positively securing said plug and said member together.

10. A device for establishing electrical connections between a power supply line and a signaling apparatus comprising in combination a cylindrical member, an enlarged body portion for said cylindrical member, a screw plug formed on one end of said enlarged body portion and arranged to be inserted in a standard lamp socket, a screw socket formed on the opposite end of said enlarged body portion, connections between said screw plug and said screw socket, and a plurality of condenser plates arranged concentrically around said enlarged body portion, with one of said plates connected with one side of the power supply line which connects said screw plug with said screw socket, whereby capacity connection may be established between another of said condenser plates and signal apparatus.

11. A device for establishing connection between a power line and signaling apparatus comprising in combination a cylindrical member, an enlarged body portion for said cylindrical member, a screw threaded plug formed on one end of said enlarged body portion and arranged to be inserted in a standard lamp socket, a screw threaded socket formed on the opposite end of said enlarged body portion and adapted to receive a standard incandescent lamp, connections between said screw threaded plug and said screw threaded socket, and a plurality of substantially semi-circular concentrically arranged condenser plates surrounding said central body portion, at least one of said plates being stationary and connected with one side of the power supply line, and another of said condenser plates being slideable in a circular plane and having means for connection to signaling apparatus for coupling said signaling apparatus capacitively with said power supply line.

12. A device for establishing connections between signal receiving apparatus and a

power supply line, comprising in combination an elongated member, a screw threaded plug on one end of said member, and arranged to engage a standard lamp socket, 5 a screw threaded socket on the opposite end of said member adapted to receive a standard incandescent lamp base, power supply connections between said screw threaded plug and said screw threaded socket, an insulated sheathing extending over the central 10 part of said elongated member, and a plurality of semi-circular condenser plates extending around the central part of said elongated member, one of said condenser plates being movable with respect to another of 15 said condenser plates, said last mentioned condenser plate being connected with one of said power supply connections, and means extending outside of said insulated sheathing for adjusting the position of said first 20 mentioned condenser plate with respect to said last mentioned condenser plate for variably coupling signaling apparatus with said power supply line.

In testimony whereof I affix my signature.
CLINTON W. HOUGH.
